PACKAGING CONTAINER FOR FOOD OR THE LIKE

Henry H. Huston, Huntington, N.Y., assignor to Lily-Tulip Cup Corporation, New York, N.Y., a corporation of Delaware

Filed Feb. 28, 1967, Ser. No. 5,987

Term of patent 14 years

(Cl. D58—17)

FIG. 1 is a side elevational view of a packaging container for food or the like embodying my new design;

FIG. 2 is a bottom plan view of the container shown in FIG. 1, the design being symmetrical about the section line 3—3;

FIG. 3 is a longitudinal sectional view taken at line 3—3 of FIG. 2; and

FIG. 4 is a fragmentary cross sectional view taken at line 4—4 of FIG. 3.

I claim:

The ornamental design for a packaging container for food or the like, substantially as shown and described.
